LUMINOUS ELECTRICAL DISCHARGE TUBE

Filed Aug. 8, 1927

ATTORNEY

UNITED STATES PATENT OFFICE

JACQUES RISLER, OF PARIS, FRANCE, ASSIGNOR TO RISLER CORPORATION OF AMERICA,
OF KANSAS CITY, MISSOURI, A CORPORATION OF DELAWARE

LUMINOUS ELECTRICAL DISCHARGE TUBE

Application filed August 8, 1927. Serial No. 211,587.

My present invention relates to luminous electrical discharge tubes and more particularly to tubes with means for cooling the electrodes.

5 In practice the amount of current which can be passed through a luminous discharge tube, and consequently the luminous capacity of the tube, is limited by the heating effect produced by the current. This effect is particularly pronounced at the electrodes. The object of my invention is to provide a means for cooling the electrodes so as to increase the luminous capacity of electrical discharge tubes.

15 The discharge tubes of my invention are constructed with perforated electrodes. Through the perforations in the electrodes and through the walls of the discharge tubes themselves pass vacuum tight pipes through which a cooling medium such as air or water 20 may be circulated.

A clearer idea of the invention may be acquired by a consideration of the accompanying drawings which illustrate, partially diagrammatically, certain forms of my invention.

Figures 1 and 2 represent the invention as applied to a mercury vapor lamp. Here the tube 1, has cylindrical ends, 2 and 3, and is equipped with lead in wires through the seals, 6. The electrodes proper are formed of metallic mercury contained in the cylindrical ends, 2 and 3. Passing through these electrode cylinders, 2 and 3, are tubes, 4 and 5 which are sealed vacuum tight through the walls of the cylinders, 2 and 3. Passage of a cooling medium, such as water or air, through the tubes 4 and 5 cools the mercury electrodes contained in the cylinders 2 and 3.

40 The lamp shown in Figure 2 is of the same type as shown in Figure 1 but is especially designed for use with air as a cooling medium. Here the tubes 4 and 5 are connected by means of the tube 7 which contains perforations, 8, that are so placed as to blow air on the main body of the lamp, 1. A single supply of air applied to the open end of tube 4 cools the whole lamp.

The mercury lamps may be formed of any suitable vitreous material, but I prefer to

make them of quartz because of the transparency and resistance to temperature changes shown by quartz.

Figure 3 shows a form of the invention suitable for producing luminous discharges in gases. The discharge tube, 9, has passing through its entire length a smaller cooling tube, 10, which is continued by means of vacuum tight joints through the ends of the tube 9. The electrodes, 11, of copper or other suitable material are formed around the cooling tube 10. Passage of air or water or other cooling media through the tube 10 cools the whole lamp.

What I claim and desire to secure by Letters Patent is:

1. A luminous electrical discharge tube including a body portion and a hollow electrode, and a tube extending along the body having laterally directed ports for discharging a cooling medium against the body and having an imperforate portion extended through the hollow electrode, for conducting a cooling medium through the electrode.

2. In a luminous electrical discharge tube having cylindrical electrode containers at each end, a cooling tube extending through opposite end walls of each container and sealed thereto and from one container to the other, said tube being separate from the discharge tube for conducting cooling medium through the electrode containers.

3. In a device of the character described, including a luminous discharge tube having electrode containers at opposite ends, and electrodes in said containers, a cooling tube extending through opposite walls of the containers and from one container to the other along the exterior of the discharge tube and having ports in said exterior portion for simultaneously cooling the electrodes and tube.

4. A luminous electrical discharge tube comprising an illuminating body portion exposed to the atmosphere and having electrode chambers at each end containing fluid electrode material and means for cooling the electrode chambers and the electrode material comprising hollow tubes extending transversely of said body portion through said electrode chambers and beyond said cham-

bers and through the electrode material contained in said chambers.

5. A luminous electrical discharge lamp including sealed electrode chambers at each end, containing metallic mercury electrodes and an illuminating body portion extending between the electrode chambers, hollow cooling tubes extending through and beyond the electrode chambers and through the mercury electrodes, and substantially at right angles to said illuminating body portion.

In testimony whereof I affix my signature.
JACQUES RISLER.
